UNIT LOADING CARGO VESSEL

Peer Lovfeld, Middletown, N. J.

Application October 16, 1940, Serial No. 361,333

2 Claims. (Cl. 114—72)

This invention relates to improvements in unit loading cargo vessels and in method of handling unit loading of various types and particularly it relates to improvements in a multi-purpose vessel which may be used for carrying trucks in peace time and which, without any changes, may be used to carry military and naval equipment such as tanks, guns, supply trucks, landing equipment, and mosquito torpedo boats in time of war.

An important object of my invention is to provide a sea-going vessel which may be used for carrying loaded or empty trucks, particularly trailer trucks, over greater distances such as in coastwise trade or even in international trade, thus making possible economical shipment by truck without unloading direct from the factory or production center to the consumer.

A further object of the invention is to provide suitable loading and unloading arrangements whereby trucks and trailers may be quickly placed in the cargo space of the vessel both on deck and under deck.

Still another object of my invention is to provide a high speed cargo vessel suitable for transporting tanks, motorized artillery, supply trucks, special landing equipment as well as mosquito torpedo boats in time of war.

Other objects and advantages of my invention will be apparent during the course of the following description:

In the accompanying drawings, forming a part of this specification, and in which like numerals are employed to designate like parts throughout the same,

Figure 1 is a shear line elevation of a vessel embodying my invention.

Figure 2 is a deck plan with crane arrangement of the vessel shown in Figure 1.

Figure 3 is a section along line 3—3 in Fig. 1.

Figure 4 is a section along line 4—4 in Figures 1 and 2, and,

Figure 5 is a section along line 5—5 in Figures 1 and 2.

In the drawings, wherein for the purpose of illustration, is shown a preferred embodiment of my invention, the numeral 10 designates the bow part of the hull 11 with the keel 12, propeller 13, rudder 14, smoke stacks 15, mast 16 and 17, etc. The hull 11 is that of an ordinary vessel except for the stern which is specially formed to provide two overhanging davits 18, which are in effect overhanging stern projections forming an extension of the hull, and a large stern port 19, see Fig. 3. The stern port 19 is preferably arranged to communicate directly with the main

deck 20 of the vessel. However, in special cases where it is desired to also carry mosquito torpedo boats, landing boats, pontoons, or similar naval equipment, the rear end of the main deck 20, designated with the numeral 21 is arranged as a slanting platform inclining down to the water line 22.

The stern port 19 furthermore communicates with a central longitudinal well opening of the main deck of the vessel and running nearly the length of the ship from the stern forward to near the pilot house 24 as indicated in Figs. 1 and 2. The engine room is placed under the main deck 20 and the two smoke stacks 15 are located one on each side of the well 23. Two rails 25, supported on the structure 26, run the entire length of the well 23 from the rear end of the stern davits 18 to the pilot house 24. On these rails are placed two traveling cranes with carriages 27, cabs 28, each having two winches 29, suitable for loading or unloading products or other equipment 30 off or on to a dock 31 as indicated in Fig. 1.

Two structures 32, each carry a set of transverse rails 33, carrying cranes with carriages 34 and winches 35 for transverse movement of the load, see Fig. 5.

The main deck 20 is provided with hatches 36 along the well 23. These hatches 36 may be opened and the unit loads 30 may be lowered to the lower deck 37. The lower deck 37 also has hatches 38 giving access to the bottom hold of the vessel where unit loads 39 may be placed if desired, see Fig. 5.

The operation of my invention is briefly as follows:

Loading and unloading of unit loads such as trailer trucks or other commercial motor vehicles in peace time and motorized artillery, landing pontoons, landing boats, or mosquito torpedo boats in time of war is accomplished by moving these loads longitudinally through the central well 23 of the vessel by means of longitudinally traveling cranes 29. When these unit loads are taken to the dock and placed on the deck by the longitudinally traveling cranes the loads 30 may be moved into final position in a transverse direction by the transverse cranes 35 on the upper deck. On the lower deck and main deck transverse movement may be effected by special rails and flat cars or trucks if necessary. By the use of this specially constructed ship and special equipment it is possible to quickly load and unload a cargo and by making the ship a high speed sea-going type it is possible to quickly transport

the cargo over large distances and again rapidly unload same at its destination. In peace time it is thus possible to relieve the congestion of arterial highways between various parts of the country and truck shipment directly from the producer to the door of the consumer is made possible at extremely low cost. The transportation cost is greatly reduced due to the fact that trailers may be used without the necessity of any drivers or cabs going with the cargo. A few drivers and cabs at the terminal points will be sufficient to gather and subsequently deliver the trailers transported by the vessel. The number of cabs and drivers will furthermore be greatly reduced because the average trips will be very short and no interstate licenses or interstate restrictions on drivers' hours will be in effect. The trucks may, therefore, be driven by one driver as required by long-haul interstate traffic. By using high speed vessels express traffic between remote parts of the country is possible with greatly reduced shipping time as compared to ordinary freight by rail.

Another very important feature of the operation of the present invention is to be found in the fact that the same ships which are used in peace time as described above may be used in war time to carry tanks, artillery, pontoons, for landing, landing boats, or even a fleet of mosquito torpedo boats. This is especially valuable in the case of mosquito torpedo boats which have normally very short range of operation. By the use of carriers or mother ships of the type described the action radius of these mosquito torpedo boats will be extended to anything desired and the carrier may follow the fleet for attacks at distant points. The carrier is particularly suited for landing of troops and mechanized equipment on distant shores. By anchoring at a suitable distance from shore with the stern pointing toward land a simple pontoon bridge may be quickly placed on which all kinds of military equipment may be landed. The special stern davits 18 and the traveling crane 29 makes it possible to launch mosquito torpedo boats in open sea and at full speed. It is also possible to pick up these boats and stow them back into the hold in open sea and under speed.

It is to be understood that the form of my invention herewith shown and described, is to be taken as a preferred example of the same, and

that various changes in the shape, size, and arrangement of parts may be resorted to without departing from the spirit of my invention or the scope of the subjoined claims.

- 5 Having thus described my invention I claim:
1. In a vessel of the character described comprising a hull, said hull having a special stern port located in the axis of said hull and being normally open to the main deck of the vessel; a plurality of stern davits extending on both sides of said stern in a rearward direction; a central passage way in said vessel, communicating with the stern port, and extending forward to the fore part of the ship; a crane rail mounted along each side of said passageway and above same; cranes located over said passageway, said cranes being motor driven and arranged for travel longitudinally on said rails over said passage way, whereby loads may be carried from the rear end of the said stern davits forward through said passage way and a plurality of transversely operated traveling cranes located over said passage way on rails supported on a steel structure traversing the vessel transversally, said rails and said steel structure being located on a higher level than said longitudinal rails on both sides of said central passage way, whereby unit loads may be stowed sidewise in said vessel.
2. A vessel for truck and unit load transportation comprising a hull, said hull having a pair of stern davits as an integral part of same; a special stern port, normally open to the main deck of said hull; a central passage way communicating with the stern port and running longitudinally along the entire main deck of the vessel; a pair of crane rails mounted one on each side of said passage way and above same, said rails extending rearward to the end of said stern davits overhanging the stern of said vessel; a steel structure built transversally upon the upper deck of said vessel, said structure extending across the entire width of said vessel above said longitudinal crane; a pair of rails mounted on said structure; a travelling crane mounted on said rails, said crane travelling transversally across said vessel and having a clearance sufficient to hoist a trailer truck above said longitudinal crane, and hatches in said main deck and between deck whereby the placing of trucks or unit loads at any desirable place in the hold is possible.

PEER LOVFALD.
